UNITED STATES PATENT OFFICE

GEORGE B. MARABLE, OF NORWOOD, OHIO

RERAILING DEVICE

Application filed November 4, 1930. Serial No. 493,313.

In re-railing a car or locomotive by pulling it back upon the tracks, it is necessary to have a device which will lift the wheels and their flanges over the top of the track or rail so that the flange can properly seat upon the inside of the rail. Devices for producing this result which have previously been constructed, have been deficient in that they have not been properly adjustable with reference to the rails, and it has been difficult and time consuming to jack the wheels into such a position as to contact with the rerailing device. These previous devices have also been so constructed as to require a considerable amount of time to properly place them in position and securely maintain them in place.

One of the objects of my invention is to provide a re-railing device which may be placed in a great many positions with reference to the tracks so that the car wheels can be brought into contact with them quickly and with facility.

Another object of my invention is to provide a re-railing device which will absolutely insure the placing of the flanged wheels on to the tracks properly.

Another object of my invention is to provide a re-railing device which can be easily and quickly placed into position and removed with the same facility after the car wheels have been placed upon the tracks.

Another object of my invention is to produce a rerailing device which is strong and simple and yet comparatively inexpensive.

In the particular embodiment of my invention selected for illustration:

Figure 1 is a plan of a section of tracks with a pair of my re-railing devices secured in position for use,

Fig. 2 is a side elevation of a portion of the track with my re-railing device placed in position for use,

Fig. 3 is a perspective of a portion of the track with one of my re-railers secured in position, and

Fig. 4 is a detail of a clamp for securing the re-railers in position.

Referring now to the drawings, my re-railor consists of a suitable base 5 which is preferably of less cross-sectional area at the

end where it is placed in contact with the track rail than the base 6 of the track rail 7. Suitable apertures not shown may be provided in the flanged base 5 of the rerailer 8, through which spikes may be driven in attaching the device to the cross-ties 9. As will be hereinafter described, it is preferable to have these apertures through the flange in order to secure the device to the cross-ties. However, I provide a clamp of such utility that the spikes may be altogether omitted. Extending up from the base 5 there is a web or rib 10 similar to the web of the track rails 7. The web 10 is tapered at its outer end 11 so that the crown 12 at this end slopes down almost to the base 5, but at the other end of the web where the re-railer comes into contact with the track rail, the web is of such height that the crown 12 may be set upon the top of the track rail when placed in position for use.

My novel clamp, see particularly Fig. 4, consists of a flat base 13 one end part 14 of which is bent upwardly and inwardly at an inclination to the base 13 whereby it is adapted to seat upon the top of the flanged bottom 6 of the track rail with the base 13 of the clamp fitting snugly against the bottom of the base 6. At its other end the clamp is bent substantially perpendicularly at 15 to the base 13, and the upper portion of the part 15 is bent inwardly at 16 to be in a plane substantially parallel to the base 13. In assembling the re-railer for use the clamp has its portion 14 seated on the top of the flange base 6 and then the re-railer is slid into place as shown in Fig. 3 so that its flanged base 5 is wedged between the members 16 and 15 of the clamp and the outside of the top of the base 6 of the track rail. The bottom of one side of the crown 12 being a flanged member will seat upon the top of the track rail. It can be seen that since the placing of the re-railer into the clamp produces a wedging action, it is not essential that spikes be driven through the re-railer into the cross-ties. However, to insure their maintenance in proper position, it is usually preferable that several spikes be driven through the re-railers into the cross-ties.

While the invention has been described above in its preferred form, it will be obvious that various changes and modifications may be made therein without departing from the spirit or scope thereof and it is therefore desired that only such limitations may be imposed thereon as are necessitated by the prior art or specifically set forth in the appended claims.

Having thus described my invention, what I claim as new and desire to secure by Letters Patent, is:—

1. A re-railer device comprising a rail having a flanged base, a substantially straight-edged crown on said rail adapted to seat on the top of a track rail and the flanged base adapted to seat on the top of the flange of the track rail, and removable means for holding said rail in seated position on the track rail.

2. A re-railer device comprising a rail element of substantially I-beam form and of substantially the height of the track rail with which it is used, except in its approach end part, where it slopes downwardly to its approach end, and means for holding the opposite end of said element to the track rail with parts of its top and bottom flanges at one side overlapping the head and base flange, respectively, of the track rail.

3. A re-railer device comprising a rail element of substantially I-beam form and of substantially the height of the track rail with which it is used, except in its approach end part, where it slopes downwardly to its approach end, and means for holding the opposite end of said element to the track rail with parts of its top and bottom flanges at one side overlapping the head and base flange, respectively, of the track rail, said approach end part being materially wider than the remainder of the length of the top flange of said element and merging into said top flange.

4. A re-railer device comprising a rail element of substantially I-beam form and of substantially the height of the track rail with which it is used, except in its approach end part, where it slopes downwardly to its approach end, and means for holding the opposite end of said element to the track rail with parts of its top and bottom flanges at one side overlapping the head and base flange, respectively, of the track rail, said top flange being substantially straight from said approach end part to the opposite end of the element.

5. A re-railer device comprising a rail element of substantially I-beam form and of substantially the height of the track rail with which it is used, except in its approach end part, where it slopes downwardly to its approach end, and means for holding the opposite end of said element to the track rail with parts of its top and bottom flanges at one side overlapping the head and base flange,

respectively, of the track rail, said approach end part being materially wider than the remainder of the length of the top flange of said element and merging into said top flange, and said top flange being substantially straight from said approach end part to the opposite end of the element.
